ELECTRIC SWITCH

Manfred J. Johnson, Naugatuck, Conn., assignor
to The Lewis Engineering Company, Nauga-
tuck, Conn., a corporation of Connecticut

Application May 26, 1937, Serial No. 144,772

12 Claims. (Cl. 200—168)

This invention relates to electric switches. An object of the invention is to provide an improved hermetically sealed electric switching device not affected by external atmospheric or other like conditions. This switching device is of particular use in aviation, in connection with the retractable landing gears of aeroplanes. For safe air travel, it is important that the retractable landing gear mechanism function properly, especially when the aeroplane is taking off, or landing. To make the position of the landing gear known to the pilot of the aeroplane at all times, the present improved switch is employed in connection with the signalling device in the cockpit of the aeroplane, the switch being associated with the landing gear to be actuated thereby for indicating whether or not the gear is located properly in extended operative position. The switching device of this invention is not affected by external pressure or water conditions, and no moisture or dirt can enter the switch housing and corrode the contacts or otherwise affect the circuit, or cause the switch to become inoperative. Also, the actuating movement required to operate the switch can be extremely small, so that any slight movement of the landing gear from its proper position will be immediately indicated in the cockpit of the plane. Associated with the small actuating movement to operate the switch are safeguard means whereby the switch is protected from injury even though there be abnormal excessive movement of the actuating means.

A switch of this type is adaptable for other uses than those in aircraft, wherever operating conditions are such as might interfere with the normal functioning of ordinary switch mechanisms, and wherever positive and reliable operation of the switch is desired. For instance, the present switch may be submerged in water tanks, in connection with floats for starting and stopping motors, or may be employed where exposure to the elements at all times is necessary and where cold or heat is present; it also has use where explosive fumes exist and sparking contacts might be dangerous.

A feature of the present improved switch structure is that it provides uniform and consistently satisfactory operation under the most severe adverse external conditions.

The switching device includes a hermetically sealed housing enclosing an electric switch unit, a waterproof assembly for the actuating mechanism of the switch, and a waterproof outlet means

for the wires connected with the switch. The actuating mechanism operating the switch proper from an external primary actuator includes a link for engaging said actuator and extending into the housing of the switch, said link operating through a compression spring and a sealing bellows to throw the switch.

Another feature of the switching device of this invention is the provision of a double seal between the external and internal actuators for the switch unit. According to the embodiment shown, the intermediary actuator or link comprises in itself a sealed unit, as well as functioning to seal the housing of the switch.

Other features and advantages will hereinafter appear.

In the accompanying drawing, showing a preferred embodiment of the invention:

Figure 1 is a longitudinal section of the switching device, the seals and actuating mechanism being clearly indicated, and the switch unit being partly in section and partly in elevation.

Fig. 2 is a sectional view taken on the line 2—2 of Fig. 1.

Fig. 3 is a sectional view taken on the line 3—3 of Fig. 1.

As shown in Fig. 1, the device of the present invention comprises a metal box or housing 10, in which is mounted a switch unit 11, and an intermediary actuating mechanism 12. The lower portion 10a of the housing comprises a separate plate secured in place by screws 10b and sealed by a gasket 10c, and said plate is provided with an aperture 10d through which extends the actuating mechanism 12 operatively connecting the switch unit with an external actuator 13.

The aperture 10d is closed on the inside of the housing by a positive watertight and airtight seal, which includes a gasket 14, a sleeve 15 passing through the aperture and having a flange 15a, and a bellows 16 one end of which is secured to the flange 15a. The inside wall of the bottom 10a of the housing is recessed at 10e to admit the flange 15a, and the latter is securely drawn up against the gasket 14 and bottom 10a by a nut 17 screwed on external threads at the lower end of the sleeve and engaging the exterior of the bottom. The upper end of the bellows is closed over and sealed by a circular plate 18 which is adapted to engage the switch unit 11 to operate same, as will be later brought out. It will be seen that the housing 10 is hermetically sealed at its lower portion by this structure.

The intermediary actuating mechanism further includes an externally threaded bushing 19

screwed into the sleeve 15 which latter is internally threaded for this purpose, said bushing being locked to the sleeve by a nut 20 as shown, and functioning as a close-fitting guide for a 5 plunger 21 engaging the primary actuator 13. The plunger 21 is operatively connected to the plate 18 by a helical compression spring 22, one end of which engages a flange 21a on said plunger and the other end of which engages the under- 10 side of the plate and is positioned thereon by a circular shoulder on the plate.

It will be seen that upward movement of the plunger 21 will cause the spring 22 to compress, and this in turn will move the plate 18 upward, 15 accompanied by expansion of the bellows 16. When the plunger is released, it will be returned to its initial lowered position under the urging of the spring 22 and bellows 16, both of which are resilient for this purpose. The plunger is 20 prevented from being completely withdrawn by the flange 21a, which engages the upper end of the bushing 19 and serves as a limiting stop.

In order to prevent any water or moisture 25 from leaking into the bellows where it might freeze or otherwise cause trouble, the lower end of the bushing 19 is packed by a felt washer 23 saturated in heavy oil and held against the end of the bushing by a nut 24 screwed over the said end. Preferably the bushing 19 has an external 30 flange 19a against which the nut 24 can be tightened.

For adjustment purposes the lower end of the plunger 21 is axially bored and threaded to carry a screw 25 locked by a nut 26. The head of the 35 screw 25 is adapted to directly engage the primary actuator 13, and the clearance between these can be adjusted by turning the screw.

The electric switch unit 11 is of a well known 40 type described in detail in Patent No. 1,960,020 issued to P. K. McGall, May 22, 1934. This switch has an important operating characteristic in that it requires an extremely small actuating movement for operation. The switch includes a movable resilient snap blade 27 adapted to engage 45 a stationary contact 28, these being respectively connected to lead wires 29 and 30, and the switch blade 27 being operated by a plunger 31 extending through the bottom of the insulating casing of the switch. The plunger 31 requires but small 50 movement to operate the switch, this being in the neighborhood of .001 inch. The upper face of the plate 18 carried by the bellows engages the lower tip of the plunger 31 so that the switch arm 27 will be actuated when the plunger 21 is 55 moved upward in response to movement of the primary actuator 13.

The insulating casing of the switch 11 is secured within the housing 10 by a pair of up-standing arms 10f carried by the bottom plate 60 10a, as shown.

Operation of the present improved switching device is as follows: Normally the switch 11 is biased so that the arm 27 engages the contact 28 to keep the circuit closed. For this condition 65 the plunger 21 is in its lowermost position wherein the flange 21a thereof engages the top end of the bushing 19. When upward pressure is applied to the lower end of the plunger 21 by the primary actuator 13 the plunger will move upward to a 70 position as shown in Fig. 1, causing the spring 22 to compress somewhat and raise the plate 18 and expand the bellows. This movement of the plate 18 will operate the plunger 31 so that the switch arm 27 disengages the contact 28, opening the 75 circuit. Because of the retarding effect of the

bellows on the spring 22, the plunger 21 will move a greater distance than the plunger 31, but the movement of each is exceedingly small as already brought out. When pressure is removed from the plunger 21 it will return to its lower 5 position under the urging of the bellows 16 and spring 22, and the switch arm 27 will return to its initial circuit-closing position.

In order to protect the switch 11 from abnormal or excessive movement of the plunger 21, the 10 top face of the plate 18 is provided with a circular shoulder 18a adapted to engage the insulating bottom 11a of the switch so that the upward movement of the plate is limited.

Further safety against excessive movement of 15 the plunger 21 is provided by the compression spring 22 operatively connecting said plunger with the plate 18, which spring can compress an extent after the plate 18 has been stopped in its upward movement. Also the lock nut 26 at the 20 lower end of the plunger is preferably so located that it will engage the lower face of the packing nut 24 to limit the upward movement of the plunger.

The top of the housing 10 is provided with an 25 outwardly extending internally threaded boss 32 receiving a nipple 33 to which is secured a metal conduit tube 34 by means of a nut 35, and the leads 29 and 30 are brought out through this nipple connection and conduit tube. The fitting 30 including the nipple 33 seals the top of the housing 10, so that no dirt nor water can enter except through the conduit 34, and this conduit and the wires passing through it are protected at their 35 other terminals to prevent this.

The lower position of the plunger 21 is determined by engagement of the flange 21a with the upper end of the bushing 19 and this lower position can be changed within limits by screwing 40 the bushing in or out, as desired.

For mounting the switching device, the housing 10 is provided with supporting arms 36 by means of which it may be secured to any desired structure.

Variations and modifications may be made 45 within the scope of this invention and portions of the improvements may be used without others.

I claim:

1. A device of the character described comprising a housing; an electric switch supported 50 in the housing; current supply means from the switch, passing through the housing; means for sealing the housing where the supply means passes through; an actuator for the switch carried within the housing; means for operating 55 said actuator from the exterior of the housing, including a plunger movably carried by the housing and having a portion extending into said housing; means for sealing the housing where said operating means is located including a bellows surrounding the portion of the plunger within the housing; and an adjustable extension on the portion of said plunger extending exteriorly 60 of said housing for engagement with an external primary actuator.

2. A device of the character described comprising a housing; an electric switch supported in the housing; current supply means from the switch, passing through the housing; means for sealing the housing where the supply means 70 passes through; an actuator for the switch; means for operating said actuator from the exterior of the housing, including a seal for said housing; and means for preventing excessive movement of the switch actuator in response to 75

- abnormal movement of the operating means, including a plurality of movement-limiting stops associated with said operating means.
3. A device of the character described comprising a housing; an electric switch supported in the housing, and an actuator therefor, said switch being adapted to operate in response to relatively small movement of the actuator; current supply means from the switch, passing through the housing; means for sealing the housing where the supply means passes through; means for operating said actuator from the exterior of the housing, including a seal for the housing; and means for preventing excessive movement of the switch actuator in response to abnormal movement of the operating means, comprising a yieldable link disposed intermediate said operating means and the switch actuator including a movement-limiting stop associated therewith.
4. A device of the character described comprising a housing; an electric switch supported in the housing; current supply means from the switch, passing through the housing; means for sealing the housing where the supply means passes through; an actuator for the switch; means for operating said actuator from the exterior of the housing, including a seal for said housing; and means for preventing excessive movement of the switch actuator in response to abnormal movement of the operating means, including a yieldable link connected with the operating means and a movement-limiting stop associated with said means.
5. A device of the character described, comprising a housing; an electric switch supported in the housing, comprising a stationary contact, a snap-arm for engaging said contact, and an actuator for said arm, said arm being adapted to operate in response to small movement of the actuator; current supply means from the switch, passing through the housing; means for sealing the housing where the supply means passes through; means for operating said actuator from the exterior of the housing, including a seal for the housing comprising a bellows one end of which engages the switch actuator; and means carried within said bellows and associated with said operating means for preventing excessive movement of the snap arm in response to abnormal movement of the operating means.
6. A device of the character described comprising a housing; an electric switch supported in the housing; current supply means from the switch, passing through the housing; means for sealing the housing where the supply means passes through; an actuator for the switch; means for operating said actuator from the exterior of the housing, including a plunger movably carried by the housing; means for sealing the housing where said operating means is located; and stops associated with the housing and plunger for limiting movement of the latter in each direction.
7. A device of the character described comprising a housing; an electric switch supported in the housing; current supply means from the switch, passing through the housing; means for sealing the housing where the supply means passes through; an actuator for the switch; means for operating said actuator from the exterior of the housing, including a plunger movably carried by the housing; means for sealing the housing where said operating means is located; and stops associated with the housing and

plunger for limiting movement of the latter in each direction, one of said stops being adjustable so that the throw of the plunger can be regulated.

8. A device of the character described, comprising a housing; an electric switch supported in the housing; current supply means for the switch passing through the housing; means for sealing the housing where the supply means passes through; an actuator for the switch; means for operating said actuator from the exterior of the housing, said means including a plunger movably carried by the housing and a yieldable link connected with the plunger; means for sealing the housing where said operating means is located; and stops associated with the housing and plunger for limiting movement of the latter in each direction, including a stop adjacent the switch actuator for preventing excessive movement of the same in response to abnormal movements of the plunger.

9. A device of the character described comprising a housing having an aperture in one of its walls; an electric switch supported in the housing; current supply means from the switch, passing through the housing; means for sealing the housing where the supply means passes through; an actuator for the switch; a bellows carried by the housing, one end of which bellows engages the switch actuator and the other end of the bellows being secured over the aperture in the housing to separate the interior of the latter from said aperture; a plunger operatively connected to the bellows and extending through the aperture in the housing; means for guiding said plunger for axial movement in said aperture, including a bushing adjustably mounted in the aperture; and movement-limiting means carried by the plunger and engaging the ends of said bushing.

10. A device of the character described comprising a housing having an aperture in one of its walls; an electric switch supported in the housing; current supply means from the switch, passing through the housing; means for sealing the housing where the supply means passes through; an actuator for the switch; a bellows carried by the housing, one end of which bellows engages the switch actuator and the other end of the bellows being secured over the aperture in the housing to separate the interior of the latter from said aperture; a plunger extending through the aperture in the housing; a compression spring connecting the plunger with the bellows; means for guiding said plunger for axial movement in said aperture, including a bushing adjustably mounted in the aperture; and movement-limiting means carried by the plunger and engaging the ends of said bushing.

11. A device of the character described comprising a housing having an aperture in one of its walls; an electric switch supported in the housing, said switch having an insulated casing; current supply means from the switch, passing through the housing; means for sealing the housing where the supply means passes through; an actuating plunger carried by the switch and extending through the casing thereof; a bellows secured to the housing, one end of which bellows engages the switch-actuating plunger and the other end of the bellows being secured over the aperture in the housing so that the bellows separates the interior of the housing from the aperture; a projection carried by the plunger-engaging end of the bellows, adapted to engage the

- insulating casing of the switch to limit movement of the bellows; a second plunger operatively connected to the bellows and extending through the aperture in the housing; means for guiding said second plunger for axial movement in said aperture, including a bushing adjustably mounted in the aperture; and movement-limiting means carried by the plunger and engaging the ends of said bushing.
- 10 12. A device of the type described, comprising a housing; an electric switch supported in the housing; current supply means from the

switch passing through the housing; means for sealing the housing where the supply means passes through the same; an actuator for the switch; means for operating the actuator from the exterior of the housing, including a link 5 passing through the housing and movably carried thereby; a seal for the housing including a bellows encasing said link and so disposed so as to be intermediate the switch actuator and the operating link; and a second seal exterior of the 10 first between the link and the housing.

MANFRED J. JOHNSON.
